Claims priority, application Germany Nov. 2, 1957
5 Claims. (Cl. 20—6)

The present invention relates to elastic floors, particularly for gymnasiums, dance halls, and the like, in which the floor covering itself or the elements which directly support such a floor, that is, the beams, timbers, or the like are supported by elastic elements which consist of wooden boards, beams, or the like extending substantially parallel to the floor surface and at suitable distances from each other, and which are subjected to bending stresses under the weight of the floor and are, in turn, mounted on a foundation which may consist, for example, of the natural soil, a solid floor, solid timbers, or the like.

In the floors which were known prior to this invention in which the floor covering itself or the elements which directly support the floor were supported by elastic members, these elastic members generally consisted of two parallel beams which were held at their ends in a spaced relation to each other by blocks or the like. Such a construction is, however, extremely sensitive and, since it consists of many different parts, it is also relatively expensive.

It is an object of the present invention to provide an elastic floor structure which permits the entire floor surface to swing perfectly uniformly and basically consists only of wood, and wherein the number of parts required is reduced to a minimum. Furthermore, the invention provides that the individual elastic supporting elements are mounted so as to prevent them from shifting relative to each other or from coming loose in any other manner.

A feature of the invention for attaining this object consists in providing an elastic floor of the general type as described in the beginning in which the elastic supporting elements consist of two pairs of substantially parallel hardwood supporting boards which are provided with recesses facing toward each other so as to form an intermediate slot, and the ends of which, which are in engagement with each other, rest upon other hardwood boards which likewise extend parallel to each other and at right angles to the upper hardwood boards.

Another feature of the invention consists in preferably interconnecting the hardwood boards forming the elastic supports of the floor covering by means of wooden pegs which extend substantially vertically through the hardwood boards.

Another feature of the invention consists in securing the supporting beams or timbers which form the direct support of the floor covering on the pairs of hardwood boards forming the elastic supporting elements by means of two boards which traverse the space between the two hardwood members of each pair and laterally abut against these timbers at both sides thereof. A very particular advantage of the invention is attained by arranging the elastic supporting elements consisting of the pairs of hardwood boards and the hardwood boards interconnecting them so as to be in a staggered relation to each other in different rows underneath the supporting timbers which directly support the actual floor boards. The elastic supporting boards preferably consist of relatively unbreakable hardwood, such as oak or ash.

An elastic floor which is designed in the manner as above described has an adequate elasticity, but one of a very definite degree which might not be entirely sufficient for each particular purpose. Thus, for example, in gymnasiums which are to be used for exercise by both

2

children and adults, the elastic floor should have a softer elasticity for the use by children than would be required by adults. Similar considerations apply if different kinds of sport or games are to be carried out which would make 5 different degrees of floor elasticity desirable.

It is therefore a further object of the present invention to provide an elastic floor of the type as described above, the elasticity of which is adjustable at any time to the particular requirements of the sports or games to be 10 carried out thereon or of the persons doing them.

This object may, according to the invention, be attained by providing suitable elements which are adapted to be inserted substantially centrally into the slots between the elastic supporting elements and which are preferably actuated so as to move simultaneously with each other to fill the slots to whatever degree may be necessary to attain the desired elasticity of the floor. For this purpose, a bar, board, or the like carrying the filling elements is 15 preferably passed transversely through the mentioned slots 20 between a series of elastic supporting boards, or the bar itself may be provided with thicker portions forming the filling elements at certain distances from each other corresponding to the distances between the elastic supporting elements. Such bars may then be adjusted in a very 25 simple manner by means of a few hand wheels which are disposed at suitable points of the floor or by means of a central mechanism which may be controlled electrically.

Further objects, features, and advantages of the present invention will be apparent from the following detailed 30 description thereof, particularly when read with reference to the accompanying drawings, in which—

FIGURE 1 shows an exploded perspective view of the essential elements of an elastic floor according to the invention;

35 FIGURE 2 shows a perspective view of the essential elements of one preferred construction of a floor with an adjustable elasticity thereof; and

FIGURE 3 is a schematic illustration showing the arrangement of a plurality of elastic support members of 40 the type depicted in FIGURE 2.

As illustrated in FIGURE 1, two substantially parallel hardwood boards a_1 and a_2 are first prepared, each having a size of about 25 x 6 x 2 cm. and spaced from each other so that their outer edges have a distance of about 40 45 to 50 cm. from each other. Then, two hardwood boards b_1 and b_2 are placed upon boards a_1 and a_2 so as to produce a square shape, as seen in a plan view. These hardwood boards b_1 and b_2 have a size of approximately 40 x 6 x 2 cm. and are each centrally hollowed out at one 50 side along a length of about 30 cm. and over the whole width of each board, the recess having a depth of approximately 4 mm. Thereafter, a pair of similar hardwood boards c_1 and c_2 with a similar recess at one side are placed upon hardwood boards b_1 and b_2 so that the two recesses together form slots d_1 and d_2 , respectively. Parallel to boards a_1 and a_2 and transverse to boards b_1 , c_1 and b_2 , c_2 , two further boards e_1 and e_2 are then placed 55 at a distance from each other so as to leave the proper space for the insertion of a square timber f upon which thereafter the counter floor g is placed which, in turn, supports the actual floor covering in the form of a plank or parquet floor h . Boards e_1 and e_2 are also made of a size of approximately 25 x 6 x 2 cm.

It will thus be seen that the entire elastic floor supporting structure may be produced by square boards of hardwood in which merely the boards b_1 , b_2 , c_1 , and c_2 are 60 chamfered to form the slots d_1 and d_2 .

These supporting frames are then placed loosely and in 65 a staggered relation to each other and at distances of about 70 75 cm. from each other upon a hard foundation of stone, concrete, mastic asphalt, tamped clay, or the like, where-

upon the square timbers *f* and the counter floor *g*, as well as the floor covering *h* may be placed thereon.

According to another feature of the invention, the hardwood boards *b* and *c* are preferably connected to each other by means of wooden pegs *i* which are fitted loosely in boards *c* so as to have a play of about 1 to 2 mm. therein so that at angular vibrations of boards *c*, these boards will not be rigidly secured to board *b* and their ability to vibrate will not be limited. The fact that the square timbers and the floor covering by themselves are capable of vibrating and that the special inventive construction of the elastic supporting elements also permits a vibration thus doubles the ability of the floor to vibrate which leads to the advantages mentioned at the beginning.

FIGURE 2 shows a modification of the invention in which the elasticity of the floor is adjustable. The hardwood boards supporting the elastic structure are indicated by *a*₁' and *a*₂'. They support the hardwood boards *b*₁' and *b*₂' which are held by suitable means, such as a spacer board, at a distance from the upper hardwood boards *c*₁' and *c*₂' so as to form intermediate slots *d*₁' and *d*₂' through which a bar *k* is passed on which at the required distances from each other small filler boards *l*₁ and *l*₂ are mounted. As shown in FIGURE 2, the bar *k* slides in cutouts *m*₁, *m*₂, of the boards *b*₁', *b*₂', respectively. Thus, when bar *k* is shifted in its longitudinal direction, filler boards *l*₁ and *l*₂ may be passed between boards *b*₁', *c*₁' and *b*₂', *c*₂' into an effective position so that the floor will then be less elastic. By means of the same adjusting mechanism, namely, the filler means which include the bar *k* and the filler boards *l*₁, *l*₂, it will also be possible to reverse this process by moving the filler boards into a withdrawn position so that the floor will have a greater degree of elasticity. Naturally, fillers of a thickness different from that of filler boards *l*₁ and *l*₂ may also be mounted on bar *k* at the other side of boards *b*₁', *c*₁' and *b*₂', *c*₂' so as to provide a third degree of elasticity of the floor.

Such adjusting mechanism is especially suitable for so-called multiple-purpose halls, for example, gymnasiums, which may also be used as assembly halls or for exhibition purposes or the like. If so used, the elasticity of the floor may be adjusted to a harder degree so that the greater weight of a large number of people on the floor will not result in any damage to the elastic elements.

As stated above, the elastic support members may be positioned in staggered relation. This is shown schematically in FIGURE 3 wherein the support members are arranged in staggered relation to each other in different rows, with a single bar *k* carrying the filler boards *l*₁, *l*₂, passing between the boards *b*₁', *c*₁', and *b*₂', *c*₂', of the elastic support members in any one row.

Although my invention has been illustrated and described with reference to the preferred embodiments thereof, I wish to have it understood that it is in no way limited to the details of such embodiments, but is capable of numerous modifications within the scope of the appended claims.

Having thus fully disclosed my invention, what I claim is:

1. An elastic floor structure, comprising, in combination: an upper floor; a plurality of elastic support members supporting said upper floor, each of said members

having two pairs of elastic hardwood boards arranged substantially parallel to the upper floor and supporting the same, said pairs being in parallel spaced relation relative to each other, the two boards of each pair of boards being arranged one above the other, being spaced from each other throughout a mid-portion of their lengths and being joined at their end portions, and transverse lower hardwood boards arranged beneath said end portions of said elastic boards and supporting the same, said transverse boards extending at substantially right angles to said elastic boards and being in parallel spaced relation relative to each other; and filler means arranged in substantially the center of the spaces formed between the two boards of each pair of elastic boards for limiting the degree of elasticity of the floor structure, said filler means including a bar carrying filler boards which are mounted on said bar and which are shiftable therewith in longitudinal direction of said bar between (1) a withdrawn position wherein each respective filler board is out of the space formed between the two elastic boards, so that substantially only the upper one of each pair of elastic boards will flex as a result of a weight being brought to bear upon the respective support member, and (2) an effective position wherein each respective filler board is in the space formed between the two boards of a pair of boards such that a flexing of the upper one of each pair of elastic boards is transmitted, via the respective filler board and said bar carrying the same, to the lower of the last-mentioned pair of elastic boards when a weight is brought to bear upon the respective support members, whereby in each position of said filler means, the support member will provide a different effective elastic support for said upper floor.

2. A floor structure as defined in claim 1, wherein said elastic support members are arranged in staggered relation to each other in different rows, and wherein said filler means passes through the spaces formed between the individual boards of the pairs of elastic boards of a plurality of elastic members which are in the same row.

3. A floor structure as defined in claim 1, wherein said end portions of said elastic boards are in direct contact with each other.

4. A floor structure as defined in claim 1, wherein said end portions of said elastic boards are joined to each other through the intermediary of spacer means.

5. A floor structure as defined in claim 1, wherein said hardwood boards are made of a material selected from the group consisting of oak and ash.
